CLAIM

The ornamental design for a multifunctional cooking pot, as shown and described.

DESCRIPTION

FIG. 1 is a front elevation view of a first embodiment of a multifunctional cooking pot, showing our new design; FIG. 2 is a back elevation view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a front elevation view of a second embodiment of a multifunctional cooking pot, showing our new design; FIG. 9 is a back elevation view thereof;

FIG. 10 is a left side view thereof;

FIG. 11 is a right side view thereof;

FIG. 12 is a top plan view thereof;

FIG. 13 is a bottom plan view thereof; and,

FIG. 14 is a perspective view thereof.

The broken lines shown in the figures depict portions of the multifunctional cooking pot that form no part of the claimed design. The shade lines shown in the figures are utilized to illustrate source contours of the claimed design and do not depict surface ornamentation.
